J. J. McBRIDE

INDICATOR FOR TANK CAR VALVES

Filed June 29, 1921

Fig. 2.

INVENTOR:
John J. McBride

BY *J. H. Gileen*

ATTORNEY.

UNITED STATES PATENT OFFICE.

JOHN J. McBRIDE, OF BAYONNE, NEW JERSEY, ASSIGNOR TO AMERICAN CAR AND FOUNDRY COMPANY, OF NEW YORK, N. Y., A CORPORATION OF NEW JERSEY.

INDICATOR FOR TANK-CAR VALVES.

Application filed June 29, 1921. Serial No. 481,376.

To all whom it may concern:

Be it known that I, JOHN J. McBRIDE, residing at Bayonne, Hudson County, State of New Jersey, and being a citizen of the 5 United States, have invented certain new and useful Improvements in an Indicator for Tank-Car Valves, of which the following is a full, clear, and exact description, such as will enable others skilled in the art 10 to which it appertains to make and to use the same, reference being had to the accompanying drawings, which illustrate the preferred form of the invention, though it is to be understood that the invention is not 15 limited to the exact details of construction shown and described, as it is obvious that various modifications thereof within the scope of the claims will occur to persons skilled in the art.

20 In said drawings:

Fig. 1 is a section taken through a tank car dome showing my improved indicator applied to the valve operating mechanism;

25 Fig. 2 is a section taken on line 2—2 of Fig. 1; and

Fig. 3 is a view of my device shown detached from the tank.

It is the object of my invention to provide an improved indicator for the discharge valves of tank cars and it is also an 30 object of my invention to provide an indicator that will insure the complete closing of the discharge valve by preventing the complete closing of the manhole cover until 35 the discharge valve is completely closed.

In the embodiment of my invention shown in the drawings, the tank is provided with the usual dome having a dome sheet 1, secured to the tank sheet 2 in any suitable 40 manner and a dome head 3 having the usual manhole opening closed by a manhole cover 4 screwed into the collar 5 secured to the dome head 3, the head 3 and sheets 1 and 2 together with the tank ends (not shown) comprising the usual tank body. A bracket 6 secured to the dome sheet 1 guides the operating shaft 7 of the tank discharge valve (not shown) and serves as an abutment for the spring 8 mounted on the shaft 7 and confined between the bracket 6 and a collar 9 fixed on the shaft 7. A hand wheel 10 attached to the upper end of the shaft 7 serves as the operating means for the shaft and valve. When the valve is completely

closed the hand wheel 10 will occupy the 55 position shown in full lines in Fig. 1 and when the valve is completely open the hand wheel 10 will occupy the position shown in dotted lines in Fig. 1.

Secured to the dome head 3 in any suitable 60 manner, as by the rivets that attach the collar 5 to the dome head 3, is a bracket 11 in which the rod 12 is slidably mounted, the bracket 11 being, as shown in Figs. 1 and 3, adapted to engage the rod 12 at a plurality of places spaced apart far enough to prevent the rod from being moved from its normal upright position. The rod 12 is headed at both ends, the bracket 11 being so positioned and the head 13 so 65 proportioned that when the rod 12 is raised the head 13 will lie in the path of the flange 14 of the manhole cover. The head 15 is shown larger than the head 13 but it need be only large enough to insure 70 that it will lie in the path of the hand wheel 10 in all positions that the rod 12 may assume in the bracket 11.

With the manhole cover removed, operating the hand wheel 10 will cause the rod 12 to be raised, projecting the head 13 into the manhole opening in a position such that the manhole cover cannot be replaced and, at the same time, indicating that the discharge valve is not in its fully closed position. Operating the hand wheel 10 to restore the discharge valve to the fully closed position will cause the rod 12 to be lowered, withdrawing the head 13 from the manhole opening, indicating that the valve is fully 80 closed and permitting the manhole cover to be completely closed.

What I claim is:

1. In a tank car, a rotary valve operating mechanism movable longitudinally and 95 a slidably position indicating mechanism for the valve projected into the manhole opening by the longitudinal movement of said valve operating mechanism.

2. In a tank car, a longitudinally movable 100 valve operating mechanism and a slidably position indicating mechanism for the valve operated by said valve-operating means adapted to prevent the closing of the manhole cover upon movement of said operating 105 mechanism from closed position.

3. In a tank car, a longitudinally movable valve operating mechanism comprising a

- hand wheel and means engaged by said hand wheel to prevent the closing of the manhole cover.
4. In a tank car, a valve operating mechanism comprising a longitudinally movable handwheel, a rod slidably supported in the path of the handwheel and adapted to be projected by said handwheel into the path of the manhole cover.
5. In a tank car having a dome, a rotary valve operating mechanism movable longitudinally and a slidable position indicator for said valve mounted on said dome and adapted to be operated by the longitudinal movement of said valve operating mechanism.
6. In a tank car having a dome, a rotary discharge valve operating mechanism movable longitudinally and slidable means car-
- ried by said dome and adapted to be operated by the longitudinal movement of said valve operating mechanism to prevent the closing of the manhole cover.
7. In a valved outlet equipment for tank cars, the combination of a tank body with an outlet and an opening, the latter to be closed by a cover or closure element, a valve to control said outlet, a bracket fixed to the body, a rod fixed to the valve and movable in said bracket, means for turning said rod, and means slidable vertically with said rod to prevent placing of the cover or closure element in closed position until the valve is closed.

In witness whereof I have hereunto set my hand.

JOHN J. McBRIDE.
